UNITED STATES PATENT OFFICE

2,554,368

TURBINE ROTOR COOLING

Walter A. Ledwith, Hartford, Conn., assignor to
 United Aircraft Corporation, East Hartford,
 Conn., a corporation of Delaware

Application August 23, 1944, Serial No. 550,887

9 Claims. (Cl. 60—41)

1

This invention relates to internally cooling the rotor of a turbine.

Cooling chambers have been placed in turbine rotors adjacent to the supporting bearings to limit heat transfer to the bearings. Since one end of the turbine rotor is generally connected to the mechanism driven by the turbine, circulation of cooling fluid into the turbine rotor at this end is difficult. If the coolant is pumped into the rotor through collector rings an extremely high pressure is required to force the coolant into the rotor against the centrifugal force resulting from the high rotational speed. An object of this invention is to overcome these objections by circulating the coolant through chambers adjacent both ends of the turbine rotor from a single coolant inlet at one end of the rotor.

In turbines driven by hot gases, circulation of coolant through the power section of the rotor has been avoided because the high temperature of the power section may produce undesirable changes in the coolant. A feature of this invention resides in directing coolant through the power section of the rotor without direct contact with its hottest parts.

A feature of this invention is the proportioning of the coolant between the chambers in the rotor to assure adequate cooling in both chambers.

Another feature is the circulation of coolant through substantially the entire length of the turbine rotor so that coolant admitted at one end will circulate through a chamber adjacent the other end.

Other objects and advantages will be apparent from the specification and claims and from the accompanying drawing which illustrates an embodiment of the invention.

Fig. 1 is a sectional view through the turbine.

Fig. 2 is a sectional view on a larger scale through the central part of the turbine rotor.

The turbine shown includes a casing 10 built up of rings 12, 14, 16 and 18 supported by radial pins 20 in a housing 22. These pins which are all in substantially the same plane and which constitute the support for the casing within the housing engage bores at bosses 24 in one ring 14 of the casing. Rotor 26 within the casing has a number of rows of blades 28 alternating with the rows of nozzles 30 in the casing.

Housing 22 has a head 34 which forms a part of the housing and supports a bearing sleeve 36 for the front end of rotor 26. At the other end

2

of the turbine, the housing 22 supports a mounting 38 within which is a bearing 40 of the shaft. The mounting has a number of legs 42 engaging radial pins 44 in the housing.

5 Rotor 26 is made up of a number of discs 46, 48, 50 and 52, each of which is substantially a constant stress disc, and shaft forming end elements 54 and 56. The discs and the end elements are all held together by a central bolt

10 58. The ends of the bolt are positioned within the end elements 54 and 56 and are connected to the end elements by threaded rings 60 and 62. Each of the rings 60 and 62 has inner and outer threads engaging respectively with cooperating threads on the bolt and on the end elements. On one of the rings the inner and outer threads may differ in pitch so that as the ring is screwed into place, a substantial tension may be applied to the bolt.

15 20 Since the casing is built up of casing rings bolted together and since the rotor is built up of discs, it is apparent that the turbine is adapted for endwise assembly. To assist in aligning the discs, each disc may have projecting annular flanges on opposite sides having interengaging elements preferably in the form of face splines cooperating with similar elements on the adjoining disc. Similarly, the inner ends of the shaft elements 54 and 56 may have face splines 25 cooperating with splines on the end discs.

30 35 Gas enters the first stage nozzles of the turbine through an inlet scroll 70 which is bolted on or otherwise attached to the end of casing 10. Gas from the turbine discharges through a duct 72 connected to the end casing ring and surrounding the rear bearing mounting.

35 40 Coolant is admitted to the rearward end of the rotor through a tube 74 mounted in one of the projecting legs 42 of the bearing mounting 38 and connecting with a passage 76 in bearing 40. A cap 78 on the bearing mounting has a connecting passage 80 by which coolant from passage 76 is guided to a tube 82 extending through a cap 84 on the end of the central bolt. 45 Coolant enters at the axis of the rotor and does not have to be pumped against centrifugal forces.

45 50 The bolt has radial passages 86 adjacent its rearward end which communicate with a chamber 88 within the rotor permitting coolant to flow through this chamber and discharge through one or more grooves 90 in the end element 56. Similarly, at the forward end of the bolt radial passages 92 permit coolant to flow 55 through a chamber 94 within the end element

54. Packing 95 surrounding the bolt and held in place by a projecting rib 96 on the bolt limits the flow of coolant along the outer surface of the bolt at the forward end. Coolant in chamber 94 discharges through radial passages 98 in end element 54 and ports 100 in a bearing sleeve 102 mounted on the end element. A cap 103 closes the end of the bolt adjacent passages 92. Packing 104 limits the flow of coolant at the rearward end of the bolt.

As shown in Fig. 2, packing 95 and similar packing 104 in end element 56 may be held in place by sleeves 106 and 108 which may be integral with sleeves 60 and 62 respectively. These sleeves have passages 110 and 112 to permit a flow of coolant from inside to outside of the sleeve.

In order that the coolant as it passes through the power section of the turbine rotor shall not be overheated a tube 114 is placed within the hollow bolt and is held in spaced relation to the inner surface of the bolt by projecting ribs 116 on the tube. At opposite ends of the tube the joint between the tube and bolt is made tight by seals or packing 118 which may be held in place by rings 120 on the ends of the tube. This packing assists in holding the tube in spaced relation to the bolt. A part of the coolant entering the rearward end of the turbine rotor flows through the tube to reach the passages 92 at the forward end of the rotor. The dimension of passage 86 is smaller than the inlet tube 82 to provide for proportioning the distribution of the coolant between the two cooling chambers. It will be understood that the tube may be omitted if it is found that the bolt does not become too hot during turbine operation.

Although the invention has been described in connection with a built-up turbine rotor it is applicable as well to a solid rotor of the type shown in the co-pending application of Ledwith, Serial No. 486,620, filed May 11, 1943, now Patent No. 2,415,104. The turbine rotor in either event constitutes a rotating shaft, access to one end of which is difficult. Coolant is circulated through a chamber adjacent one end of the shaft or rotor by causing it to flow through an axial passage in the rotor from the opposite end to which coolant may be admitted centrally of the shaft axis.

It is to be understood that the invention is not limited to the specific embodiment herein illustrated and described, but may be used in other ways without departure from its spirit as defined by the following claims.

I claim:

1. In a turbine, a rotor having a power section with at least one row of blades extending therefrom, axially spaced chambers adjacent opposite ends of the rotors, and means for directing fluid to all of the chambers from one end of the rotor, said means including an axial passage in the rotor extending through the power section and interconnecting the chambers, a conduit for the fluid within and spaced from the walls of said passage and interconnecting the chambers, and sealing means around the conduit to keep the fluid out of the space surrounding the conduit.

2. In a turbine, a rotor having a power section with at least one row of blades, spaced chambers located at opposite ends of the rotor, spaced bearings for the rotor located adjacent to said chambers, and means for directing fluid to both of the chambers from one end of the rotor, said

70

75

means including an axial passage in the rotor extending through the power section and interconnecting the chambers, a conduit for the fluid within and spaced from the walls of said passage and interconnecting the chambers, and sealing means around the conduit to keep the fluid out of the space surrounding the conduit.

3. In a turbine, a rotor having a power section with at least one row of blades and a shaft

10 extension at each end of the power section, each shaft extension having a chamber therein, a bearing surrounding each shaft extension and located adjacent to the chamber in each of said shaft extensions, means for directing coolant to both chambers from one end of the rotor, said means including a passage in said rotor extending between and interconnecting said chambers, and a conduit within and spaced from the walls of the passage and through which the coolant flows out of contact with the walls of the passage, and passages extending through each shaft extension and communicating with the adjacent chamber through which the coolant in the chambers may be discharged from the rotor.

20 4. In a turbine, a rotor having a power section with at least one row of blades and a shaft extension at each end of the power section, each shaft extension having a chamber therein, a bearing surrounding each shaft extension and located adjacent to the chamber in each of said shaft extensions, means for directing coolant to both chambers from one end of the rotor, said means including a passage in said rotor extending between and interconnecting said chambers, and a conduit within and spaced from the walls of the passage between the chambers through which the coolant flows, and sealing means around the conduit to keep the fluid out of the space surrounding the conduit.

25 5. In a turbine, a rotor having a power section and a shaft extension at each end of the power section, each shaft extension having a chamber therein, a bearing adjacent each chamber and surrounding each shaft extension, means for directing coolant to one of the chambers through the adjacent end of the rotor, a passage in said rotor connecting the chambers and a conduit within and spaced from the walls of the passage for flow of coolant from said 30 one chamber to the other chamber without contacting the passage walls, and passages in the rotor adjacent each end and communicating with each of said chambers for the escape of coolant therefrom.

35 6. In a shaft, a chamber adjacent one end, a passage from said chamber to the other end of the shaft, means for directing fluid through said passage to said chamber, said means including a tube within and spaced from the walls of the passage, sealing means around the tube to keep fluid out of the space surrounding the tube, and a discharge passage extending radially of the shaft adjacent to said chamber for the escape of fluid.

40 7. In a shaft, a chamber adjacent one end, a passage from said chamber to the other end of the shaft, a bearing surrounding said shaft adjacent to the chamber, and means for directing fluid from said other end of the shaft to said chamber including a tube within and spaced from the walls of the passage, sealing means around the tube to keep fluid out of the space surrounding the tube, and a discharge passage extending radially of the shaft adjacent to said chamber for the escape of fluid.

8. In a turbine rotor, a chamber adjacent one end, a passage through said rotor from said chamber to the other end, a bearing surrounding said rotor adjacent to said chamber, and means for directing coolant to said chamber from said other end of the rotor, said means including a tube within and spaced from the walls of the passage and extending from said chamber to said other end of the rotor, sealing means around the tube to keep fluid out of the space surrounding the tube, and a discharge passage extending radially of the rotor adjacent to said chamber for the escape of fluid.

9. In a turbine rotor, a chamber adjacent one end, a passage through said rotor from said chamber to the other end, a bearing surrounding said rotor adjacent to said chamber, and means for directing coolant to said chamber from said other end of the rotor, said means including a tube within and spaced from the walls of the passage and extending from said chamber to said other end of the rotor, sealing means around the tube to keep fluid out of the space surrounding the tube, said tube tapering toward said one end of the rotor, and a discharge passage extending radially of the rotor adjacent to said chamber for the escape of fluid.
